his attorney.

UNITED STATES PATENT OFFICE.

LORENZO A. STEWART, OF WAUKEGAN, ILLINOIS.

HERNIAL TRUSS.

SPECIFICATION forming part of Letters Patent No. 703,847, dated July 1, 1902.

Application filed August 17, 1900. Serial No. 27,201. (No model.)

To all whom it may concern:

Be it known that I, LORENZO A. STEWART, a citizen of the United States, residing at Waukegan, in the county of Lake and State of Illinois, have invented certain new and useful Improvements in Trusses; and I do hereby declare the following to be a full, clear, and exact description of the invention, such as will enable others skilled in the art to which it appertains to make and use the same.

The object is to provide a simply-constructed and thoroughly efficient form of truss for use in cases of inguinal hernia, either external or oblique or internal or direct.

15 The invention consists in the novel form of truss-pad, together with other features of construction of the truss as a whole, as will be hereinafter fully described and claimed.

20 In the accompanying drawings, forming a part of the specification, and in which like letters of reference indicate corresponding parts, I have illustrated a form of embodiment of my invention, it being understood that the same may be varied without departing from the spirit of the invention, and in these drawings—

25 Figure 1 is a view in perspective, exhibiting the trunk of the human figure with the truss positioned thereon. Fig. 2 is a view in plan, 30 exhibiting the pad detached from the truss. Fig. 3 is a view in transverse section, taken on the line 3-3, Fig. 2, exhibiting the construction of the pad; and Fig. 4 is a view in plan, exhibiting the truss as a whole.

35 Referring to the drawings, A designates the pad, B the waist-strap, and C the center strap. The waist-strap C has adjustably connected with it a short strap b, carrying a plate b², provided with an opening, and the center 40 strap carries a similar plate c, the function of these two plates being described fartheron.

45 The invention resides particularly in the pad. This pad is by preference made of metal, preferably of aluminium on account of its lightness and its non-oxidizing properties, and is provided with an enlarged head a, which is hollowed out, as at a², for lightness, leaving a center core a³ and a surrounding rim a⁴. From the head the pad gradually 50 tapers and is curved inward from its securing belt and toward the body of the wearer to form a horn or finger a⁵. The outer or back-

curved surface of this horn or finger is hollowed out, as shown at a⁶, to present edges or flanges a⁷ for engaging with the part carrying the pad, thereby to hold the pad in position against shifting laterally when positioned on the wearer.

55 The pad-carrying portion b³ of the waist-strap is constructed, preferably, of leather on the outside and velvet or other soft yielding material on the inside, the particular function of the velvet being to permit the edges or ribs a⁷ to sink thereinto, and thus prevent the shifting of the pad in use. The pad is 60 secured in position on the waist-strap by a screw a⁸, which passes through a plate a⁹ on the outer side of the strap and into the pad. While the screw is herein shown, it is to be understood that I do not limit my invention 65 to this particular form of holding means, as a rivet or other suitable fastening device may be employed. The plate a⁹ carries two headed lugs a¹⁰ and a¹¹, arranged on opposite sides of the plate a⁹, the lug a¹⁰ to be engaged by 70 the plate c of the center strap C and the lug a¹¹ to be engaged by the plate b² of the waist-strap.

75 When the truss is positioned as shown in Fig. 1, the horn or finger a⁵ will be caused to 80 press against the inguinal canal, and the plate b² will then be brought into engagement with the lug a¹¹. The center strap will then be passed between the legs of the wearer on one side of the scrotum and the plate c brought 85 into engagement with the lug a¹⁰. When thus positioned, the truss will be held in position against shifting, and owing to the manner in which it is constructed and adjusted will be found to be very easy to wear, obviating all inconvenience and pain to the user, such as accompanies the use of most truss-pads employed for the treatment of inguinal hernia.

90 Having thus fully described my invention, what I claim as new, and desire to secure by Letters Patent of the United States, is—

1. As a new article of manufacture, a truss-pad formed with a flat bearing-surface substantially circular in outline and an inflexible horn projecting therefrom, the horn being curved toward the body of the wearer and away from the supporting-strap, substantially as described.

2. A truss-pad comprising a body portion substantially circular in outline, a horn formed integral with the body portion and extending therefrom, the body portion adapted to be centrally pivoted to a securing-strap, thus enabling the horn to be brought to bear upon different portions of the anatomy about the body portion as a center, without altering the application of the body portion, substantially as described. 30
5. A truss comprising a pad formed with a flat body portion and a curved horn or finger 35 hollowed out to form ribs extending therefrom, the said horn being curved and adapted to extend inward into contact with the body of the wearer, when the pad is in position, means for securing the pad to the body of the 40 wearer, and yielding material interposed between the securing means and the ribs of the horn, substantially as described.
3. As a new article of manufacture, a truss-pad formed wholly of non-corrosive metal, and having a flat body portion, and a horn or finger, the pad being provided upon its back 45 with projecting ribs, the said horn being curved and adapted to extend inward into contact with the body of the wearer, when the pad is in position, substantially as described.
4. In a truss, the combination with a securing-strap, of a pad, the body portion thereof presenting a flat bearing-surface substantially circular in outline, an inflexible horn integral with the body portion and projecting therefrom, said horn being curved inward toward the body of the wearer and away from the securing-strap and terminating beyond the plane of the bearing-surface of the body portion, the body portion centrally pivoted to the securing-strap, thus adapting the 50

curved horn to be brought to bear upon different portions of the anatomy without altering the application of the body portion, substantially as described.

5. A truss comprising a pad formed with a flat body portion and a curved horn or finger 35 hollowed out to form ribs extending therefrom, the said horn being curved and adapted to extend inward into contact with the body of the wearer, when the pad is in position, means for securing the pad to the body of the 40 wearer, and yielding material interposed between the securing means and the ribs of the horn, substantially as described.

6. A truss comprising a waist-strap carrying a plate, a center strap also carrying a 45 plate, a pad carried by the waist-strap, the pad having a flat body portion, and a curved horn or finger, the horn or finger having its back formed with one or more ribs and yielding material interposed between the waist- 50 strap and the ribs, substantially as described.

In testimony whereof I affix my signature in the presence of two subscribing witnesses.

LORENZO A. STEWART.
